Radio Corporation of America, a corporation of Delaware

Application May 25, 1953, Serial No. 356,940

10 Claims. (Cl. 271—2.3)

This invention relates to film advancing apparatus, and particularly to a damping unit used in obtaining a constant and uniform film speed at a sound translation point.

Film drive systems for sound recording and reproduction, wherein a drive sprocket is used for advancing perforated film, are well-known. These systems generally have a film-pulled drum with a flywheel on its shaft and a tensioned filter in the loop between the sprocket and drum. In such systems, it has been found desirable to introduce friction or a drag at some point in the mechanism. For instance, felt friction pads on the sound drum ball bearings have been used, as well as friction applied directly to the flywheel on the drum shaft. Furthermore, various frictional devices have been applied to the pressure roller. However, in all these instances, this type of frictional application does not completely solve the problem.

Other forms of damping have been in the form of eddy current brakes on the flywheel or a viscous drag on the flywheel by running it in oil or water. It was found that viscous resistance gave better results, because it contributed to the damping of the system. Adding a resistance of any nature to the flywheel or sound drum had two important bad effects. One was to limit the effectiveness of the flywheel, and the other was to cause slippage of the film on the sound drum. These two effects limited the usefulness of this method of applying damping, even though it proved that viscous friction was preferred over mechanical friction.

The present invention avoids these two bad effects by applying a viscous friction to the pressure roller which holds the film on the sound drum. By the use of silicon oil, which is not subject to viscosity changes with temperature within the range of temperatures to which it is subjected, and placing this oil within the pressure roller, not only the amount of drag obtained can be controlled by varying the viscosity of the silicon, but also this drag may be controlled by the amount of clearance or space provided within the roller for holding the silicon oil. The application of viscous friction by the pressure roller causes no slippage between the drum and the film. Also, because the resistance or drag is at the pressure roller, the additional tension in the film more tightly binds the film to the sound drum, and thereby makes the flywheel more effective as a film stabilizing factor.

Furthermore, since there is sufficient tension in the film loop between the sprocket and sound drum, the resilient filter in the loop can be damped so as to effectively minimize oscillation in the over-all system. The invention is particularly adaptable for introducing viscous friction in a loose loop film path of film recorders and reproducers at the pressure roller so that the advantages of a tight loop system can be incorporated in a loose loop system and still preserve all of the inherent advantages of the loose loop system.

The principal object of the invention, therefore, is to facilitate the constant and uniform advancement of film.

Another object of the invention is to provide an improved constant and uniform film advancing drive mechanism.

A further object of the invention is to provide an improved damping element for a constant speed film advancing mechanism.

Although the novel features which are believed to be characteristic of this invention will be pointed out with particularity in the appended claims, the manner of its organization and the mode of its operation will be better understood by referring to the following description, read in conjunction with the accompanying drawings, forming a part hereof, in which:

Fig. 1 is an elevational view of a film drive mechanism embodying the invention.

Fig. 2 is a cross-sectional view of one modification of a damping pressure roller used in the system of Fig. 1, and

Fig. 3 is a cross-sectional view of another modification of the damping pressure roller shown in Fig. 2.

Referring now to Fig. 1, a film drive system is mounted on a mounting plate 5, which may be part of a picture projector. A film 6 may come from a supply reel or from the intermittent advancing mechanism of a picture projector. It passes in a loop over guide roller 7, over a stabilizing drum 8, which has a flywheel on its shaft, then into an S loop around filter rollers 10, over a film advancing sprocket 11 with its shoe 12, and then to a holdback sprocket 14 with its shoe 15. A portion of an optical sound reproducing assembly is shown at 17. The shoes and other elements are mounted on the plate 5 in the usual manner, such as by screws 9 and 13.

The jockey or filter roller unit 18 having rollers 10 is of the type disclosed in Bartelson U. S. Patent No. 2,685,417 of August 3, 1954. In brief, this unit comprises the rollers 10 mounted on the diametrically opposite ends of a sector-like plate 20 fixed to a rotatable shaft 21 on the other end of which is wound a spring encased in a housing filled with oil, preferably silicon. The movable plate 20 has an arcuate, elongated slot 22 therein for reception of a fixed pin 23, the slot and pin acting as a limiter for the movement of the rollers 10.

The film 6 is in a tight loop between the sprocket 11 and the drum 8, and the tightness is controlled by the adjustment of the tension applied to the filter rollers 10. The film is in a loose loop as it approaches roller 7 and contacts the drum 8. Mounted adjacent the drum 8 and applying pressure to the film thereon in any suitable manner, such as by a spring, is a pressure roller 25 having a rubber or neoprene tire 26 thereon (see Fig. 2). The roller shown in Fig. 2 has a sleeve bearing, while the roller shown in Fig. 3 has roller bearings.

Referring now to Fig. 2, the roller is formed of an inner cylindrical member 28 mounted on an arm 29 by a screw 30. The member 28 has radial holes or openings 32 and an annular recess 33 in the outer central portion of its cylindrical wall. Mounted for rotation on the member 28, is a cylindrical bearing member 35, on one end of which is a guide flange 36 having a recessed cylindrical portion for supporting the tire 26. The remaining element of the roller is an outer flange 40, which has a lip 42 fitted into the member 35 so that centering will be maintained. The flange 40 is attached by screws 41 to the cylinder 35. Before flange 40 is assembled, the central portion of the roller is filled with silicon oil 44. The oil in this reservoir passes through the openings 32 to the outer recess 33, where it exerts a viscous drag on the rotating elements of the roller, and thus provides the improved viscous friction mentioned above.

Referring now to Fig. 3, this roller construction has a central cylindrical member 50 attached to an arm 51

by a screw 52. At the ends of a narrower diameter section of the member 50 are mounted ball bearings 57 and 58, which are properly located axially by spacer 73 and secured by screw 75. A rotatable cylinder 61 is mounted on the bearings, on the right-hand end of which is a guide flange 62. The central portion of the cylinder 61 is recessed to accommodate a tire 63, which may be of neoprene or rubber similar to the tire 26 shown in Fig. 2.

This roller in Fig. 3 has an outer flange 65 with a lip 66, which is fitted into the cylinder 61 for centering and for making secure the ball bearings 57 and 58, the flange being attached to cylinder 61 by screws 67. Similarly to the roller shown in Fig. 2, silicon oil 69 is placed at the center of the roller before the flange 65 is assembled. This oil passes through openings 77 and 79 and into the clearance 71 between the spacer 73 and the cylinder 61. The oil, which is also in the bearings 57 and 58, introduces to the rotating portions of the roller a viscous resistance which has been found to provide the necessary drag discussed above, thereby providing a loose-loop constant speed film drive system with the advantages of a tight loop system.

A feature of the above construction is the manner in which the silicon oil is held within the rollers. The fit at 81 between the member 28 and flange 36 permits free-running of the flange, but close enough so that the clearance is bridged by the oil which is held in place by surface tension. This provides a static capillary seal when the roller is at rest, the fluid eventually flowing or draining back into the reservoir. When the roller is running, the difference in velocity between the inside surface of the cylinder 35 and the outer surface of cylinder 28 as at point 85, reduces the pressure at the point 81 as the flow of oil is from the center of the roller to the outside thereof. This produces a dynamic velocity seal against leakage when the roller is operating.

These types of sealing actions are also present in the roller bearing roller of Fig. 3. In this construction, the difference in velocity is produced by the difference between the diameter of the small shoulder of member 50 and the diameter of the inner races of the ball bearings 57 and 58.

I claim:

1. In a film drive system having a drive sprocket for pulling film over an inertia drum, a drive sprocket, an inertia drum, a tensioning means between said sprocket and drum, said film being adapted to approach said drum in a loose loop and pass over said tensioning means to said sprocket in a tight loop, a pressure roller, means for supporting said roller for movement into and out of contact with said drum, said roller being adapted to contact film passing over said drum, and means within said roller for applying a uniform internal viscous drag to the surface of said roller and a resistance to the passage of film over said drum, said viscous drag means including a fixed inner cylinder and an outer cylinder rotatable with respect to said inner cylinder.

2. A film drive system in accordance with claim 1 in which said tensioning means between said sprocket and said drum forms an S path for film adapted to pass between said sprocket and drum.

3. A film drive system in accordance with claim 1 in

which silicon oil is provided between said cylinders to provide said viscous drag.

4. A viscously damped roller comprising a fixed hollow cylindrical member, a second cylindrical hollow member surrounding and rotatable with respect to said fixed cylindrical member, oil within said fixed member, a space being provided between said fixed member and said rotatable member, said fixed member having centrally located openings therein to permit said oil to flow therethrough into said space, and a closure member for one end of said rotatable member for holding said oil in said fixed member and centering said rotatable member thereon.

5. A viscously damped roller in accordance with claim 4 in which said rotatable member has a guide flange at one end thereof, said closure member forming a guide flange at the other end of said rotatable member, and an anti-slip tire around the central portion thereof.

6. A viscously damped roller in accordance with claim 5 in which said oil is silicon.

7. A damping roller comprising a central fixed cylindrical member, ball bearings mounted on and adjacent the ends of said member, a rotatable member mounted on said ball bearings, oil within the central portion of said fixed member, and openings in said first mentioned member for passing oil within said member to said ball bearings.

8. A damping roller in accordance with claim 7, in which guide flanges are mounted at the ends of said rotatable member and an anti-slip tire is over the central portion of said rotatable member.

9. A damping roller in accordance with claim 7, in which said oil is silicon.

10. A viscously damped roller comprising a fixed hollow cylindrical member having a cylindrical wall and one end open, a second hollow cylindrical member surrounding and rotatable with respect to said fixed cylindrical member and having one end open, oil within said fixed member, said fixed member having an annular recess in the outer central portion of its cylindrical wall and openings therein passing through said cylindrical wall from the interior of said fixed member to said recess, and a closure member for the open ends of said cylindrical members for holding said oil in said fixed member and centering said rotatable member thereon.
